US0D1039445S

(12) **United States Design Patent** (10) Patent No.: **US D1,039,445 S**
(45) Date of Patent: ** Aug. 20, 2024

(54) **ELECTRIC BICYCLE**

(71) Applicant: **SHENZHEN KIXIN ELECTRONICS CO., LTD**, Shenzhen (CN)

(72) Inventor: **Wu He**, Shenzhen (CN)

(73) Assignee: **SHENZHEN KIXIN ELECTRONICS CO., LTD**, Shenzhen (CN)

(**) Term: **15 Years**

(21) Appl. No.: **29/867,730**

(22) Filed: **Nov. 6, 2022**

(51) LOC (14) Cl. **12-11**

(52) U.S. Cl.

USPC **D12/111**

Primary Examiner — Darlington Ly

(57) **CLAIM**

The ornamental design for an electric bicycle, as shown and described.

DESCRIPTION

FIG. 1 is a top, rear and left side perspective view of an electric bicycle embodying my new design;

FIG. 2 is a bottom, front and right side perspective view thereof;

FIG. 3 is a left side elevation view thereof;

FIG. 4 is a right elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a partial and enlarged perspective view of area 9 in FIG. 1; and,

FIG. 10 is a partial and enlarged perspective view of area 10 in FIG. 2.

The dot-dash broken lines serve as graphical annotations that indicate the areas of enlargement shown in FIGS. 9 and 10 and do not represent actual structures.

1 Claim, 10 Drawing Sheets
